UNITED STATES PATENT OFFICE.

FRANK D. FARNAM, OF CHICAGO, ILLINOIS.

CLEANING DEVICE FOR UTILIZING VOLATILE LIQUIDS.

1,137,959.

Specification of Letters Patent.

Patented May 4, 1915.

Application filed November 15, 1912. Serial No. 731,591.

To all whom it may concern:

Be it known that I, FRANK D. FARNAM, a citizen of the United States, and a resident of Edison Park, Chicago, in the county of Cook and State of Illinois, have invented certain new and useful Improvements in Cleaning Devices for Utilizing Volatile Liquids; and I do hereby declare that the following is a full, clear, and exact description of the same, reference being had to the accompanying drawings, and to the numerals of reference marked thereon, which form a part of this specification.

Considerable danger and frequent loss of life or serious injury, is occasioned through the use of volatile liquids such as gasolene, benzene, naphtha, ether, and other similar liquids used in cleaning. These accidents usually occur from the use of a volatile and highly inflammable liquid, sometimes used from open dishes, the vapors from which soon saturate the atmosphere to an extent that a spark produced from any cause, is sufficient to cause an explosion and fire. Sometimes in washing silk in gasolene or naphtha, the rubbing of the silk may produce a sufficient electrical spark to ignite the exceedingly inflammable gases surrounding the same with the result of a very serious or fatal accident.

The object of this invention is to afford a device whereby the cleaning liquid is at all times inclosed, and free volatilization thereof to the atmosphere is entirely prevented, and whereby a limited and restricted volatilization occasioned by the warmth of the hand of the user, or by any other suitable means is sufficient to discharge to the surface to be cleaned, the requisite amount of the cleaning fluid for the purpose intended.

It is an object of the invention to afford a construction whereby the flow of the cleaning fluid is occasioned by the heat of the hand of the user, and whereby should the use be discontinued further delivery of the volatile fluid immediately ceases.

It is also an object of the invention to afford an exceedingly simple, durable, effective, and absolutely safe device for the purpose described, adapted for immediate and instant use when required, and so constructed as to obviate loss through leakage.

The invention (in a preferred form) is illustrated in the drawings:

In the drawings: Figure 1 is a central, 55 vertical section of a device embodying my invention. Fig. 2 is a section thereof on line 2—2 of Fig. 1. Fig. 3 is an enlarged sectional detail of the valve. Fig. 4 is a view similar to Fig. 1, but illustrating a 60 container having a slightly different shape for convenience in handling. Fig. 5 is a section similar to Fig. 1, and illustrating a somewhat different valve construction. Fig. 6 is an enlarged, fragmentary detail and 65 section of the construction illustrated in Fig. 5. Fig. 7 is a top plan view of the same. Fig. 8 is an enlarged, top plan view of the spider for centralizing the valve rod.

As shown in the drawings: A container 70 comprising a tube 1, having a cap 2, fitted thereto, and, if preferred, threaded thereon to permit filling, is threaded into a fitting or coupling 3, the outer end of which may be of larger diameter and is internally threaded 75 to receive therein the suitably threaded back or end 4, of a cleaning or rubbing element of any description, but as shown consisting of a brush 5, which conveniently is provided with relatively stiff bristles, which converge 80 toward the center. Secured at the inner end of the tube on its closed head 6, is a valve casing 7, having an inwardly opening passage in its bottom, through which the gasolene or other volatile liquid may flow thereinto, and containing a ball closure 8. Threaded into said valve casing is a complementally shaped head or seat 9, having a passage opening upwardly therethrough and communicating with a bent tube 10, 90 which extends upwardly in said tube to near the upper end thereof and thence downwardly with the end thereof extending into a passage 15^a opening through the head 6, and the brush back, as shown in Fig. 1. 95 Said pipe, of course, is soldered or otherwise connected in the head 6, of the tube to afford a tight joint, and the bottom of the valve casing 7, is elevated sufficiently above the head 6, to permit the volatile liquid to flow therebeneath and upwardly therethrough through the normally closed passage when the liquid is subjected to sufficient pressure.

The construction illustrated in Fig. 4, is identical with that before described, except 105 that the tube 1, is integrally connected with a transverse tube 11, affording a handle, and in which the loops of the tube 10, extend to

near the opposite ends thereof. One end of said transverse handle 11, is provided with a screw cap 12, to permit filling.

In the construction illustrated in Figs. 5 to 8 inclusive, the tube 13, has threaded into the lower end thereof the head 14, provided with a central aperture and having secured thereto on the under side thereof, a conical downwardly tapering discharge nozzle 15, united with which centrally is a discharge pipe 16, which extends through the coupling 3, before described, and communicates with the passage 15^a through the brush back 4. A spider 17, is seated in the upper end of the tube and extending through the same and through said aperture in the head 14, and provided with a valve closure 18, on the lower end thereof, is a stem 19, provided at its upper end with a rounded head 20, where-by the stem may be pressed inwardly. A spring 21, is engaged within the conical nozzle 15, and bears upwardly against the closure 18, to hold the same normally seated. Threaded on the upper end of the pipe and fitting to the cylindric stem 22, integral with the spider 17, is a screw cap 23, which is removable to permit the filling of the reservoir afforded by said tube.

The operation is as follows: The article to be cleaned is spread upon a suitable surface and the cleaning tool embodying my invention is grasped with the hand and rubbed back and forth thereover. Owing to the small discharge outlet in the form of device illustrated in Figs. 4 to 6 inclusive, none of the fluid will escape from the container even though no valve be used until pressure is generated within the container by the volatilization of the liquid within the container to an extent to produce more than atmospheric pressure. After the device has become slightly warmed, the valve may be opened by pressing upon the thumb piece 20, whereupon a few drops of the volatile liquid will be delivered downwardly through the brush and thus spread over the surface to be cleaned. With the release of such pressure, however, the flow immediately stops until further pressure is generated, when the operation continues as before.

In the construction illustrated in Figs. 1 to 4 inclusive, the operation of the device is wholly automatic when the temperature is raised by the heat of the hand of the user. When it is desired to use the device, the article is spread upon a suitable surface for cleaning and the operator grasping the container in the hand rubs the brush upon the surface to be cleaned. Inasmuch as the walls of the container are relatively thin and the device is constructed of copper or other suitable conducting material, the heat of the hand is almost instantly communicated to the volatile liquid, volatilizing a sufficient portion thereof to create pressure, unseating

the ball 8, and opening the passage into the valve casing 7. The liquid now passes upwardly through the pipe 10, and will be discharged drop by drop to the brush, as required.

The diameter or bore of the pipe is sufficiently small as to permit but slow delivery of the liquid, and that approximately to the requirements for satisfactory use of the device. Should the use of the device be discontinued, the moment the hand releases the same, condensation occurs and the flow ceases. Should the device by any possibility be laid down in a position where the liquid might possibly drain therefrom, the small size of the bore of the pipe 10, and the fact that the container is air tight even independently of the seating of the ball 8, in the upper seat of the casing or that controlling the passage leading into the pipe 10, will be sufficient to prevent loss of the liquid.

In the construction illustrated in Fig. 4, the device is shown with a container suitably formed to afford a large surface area for contact with the hand and also so formed as to permit the same to be used without danger of tiring the hand, as, for instance, in tailoring establishments and elsewhere where the device may be used continuously for considerable periods of time.

Of course, it is to be understood that a pad may be substituted for the brush shown, and that many other details of the construction may be varied, without departing from the principles of my invention. I have shown but a preferred form of the invention, and therefore do not purpose limiting the patent granted otherwise than necessitated by the prior art.

I claim as my invention:

1. A cleaning device for utilizing volatile liquids embracing a container, a brush secured thereon, a passage communicating with the container and leading to the brush, and means operated by the heat of the hand of the user for delivering the contents from the container to the brush drop by drop.

2. A thin walled air-tight container for a volatile liquid, a brush secured on the container, a passage communicating with the container and leading to the brush, a valve normally closing said passage, and means operated by the heat of the hand of the user for delivering the contents from the container to the brush.

3. A cleaning device for utilizing volatile liquids embracing a thin walled container shaped to fit the hand, a brush secured thereon, an air-tight closure for the container adapted for removal to permit filling, a passage communicating with the container and leading to the brush, and a valve controlling said passage to prevent the escape of the volatile fluid from the container, and adapted to be opened by the volatilization

- of the fluid within the container when subjected to the heat of the hand.
4. A cleaning device for utilizing volatile liquids embracing a container shaped to fit the hand, a brush thereon, an air-tight closure for the container adapted for removal to permit filling, a pipe opening through the brush back and extending upwardly into and around the container, and a normally closed valve at the inner end of the pipe adapted to be unseated by internal pressure occasioned by the heat of the hand of the operator to permit delivery of the liquid therethrough to the brush.
5. A cleaning device for utilizing volatile liquids embracing a brush, a container, and means operated by the heat of the hand of the user for discharging the contents of the container drop by drop, to the brush.
6. A cleaning device for utilizing volatile liquids embracing a container for the volatile fluid, a brush secured thereto, a pipe opening through the brush back and extending upwardly into and around the container, and a valve at the inner end of the pipe operated by pressure produced by the heat of the hand of the user for slowly discharging the contents of the container.
7. A container for a liquid having a cap secured at one end thereof, a coupling engaged on the other end of the container, a cleaning element fitted in said coupling, a valve within, and normally spaced from the bottom of the container to permit the liquid to flow therebeneath and upwardly therethrough, and a tube communicating with the valve and leading to the brush, said valve opened by the increase in pressure within the container caused by the heat of the hand of the user to permit the liquid to flow from the container to the brush through said tube.
8. A cleaning device for utilizing volatile liquids embracing a container, a cleaning element secured thereon, a valve casing open at both ends mounted in said container, a gravity acting ball closure therein adapted to close either end thereof, and a bent tube communicating with the valve casing and extending to near the upper end of said container and then downwardly with the end of said tube leading to the brush.
9. In a cleaning device utilizing volatile liquids the combination with a rubbing element, of means operating by the heat of the hand of the user to cause discharge of the liquid through said rubbing element.
10. A cleaning brush utilizing volatile liquids operated by the heat of the hand of the user to cause discharge of the liquid to the brush to clean an article.
- In testimony whereof I have hereunto subscribed my name in the presence of two subscribing witnesses.
